UNITED STATES PATENT OFFICE.

LYMAN W. CLOSE, OF TOLEDO, OHIO, ASSIGNOR TO THE TOLEDO PRESSED STEEL COMPANY, OF TOLEDO, OHIO, A CORPORATION OF OHIO.

CONSTRUCTION TORCH.

Application filed November 24, 1926. Serial No. 150,404.

This invention relates to torches of the type used as signals on construction work, and objects of this invention are to provide a novel and serviceable sheet metal, self-righting torch, which is simple in construction and consequently inexpensive to manufacture; to provide new and improved means for holding a counter-weight in place in a torch of this type, such means being reliable and efficient; and to provide a self-righting torch having the new and improved features of construction hereinafter described.

The invention is shown by way of illustration in the accompanying drawings in which:

The figure is an elevation partly in section of a construction torch.

The illustrated embodiment of the invention comprises a construction torch in the form of a truncated-sphere having two equal parts, an upper part 1 and a lower part 2. These parts are welded together in a well known manner, thereby forming an annular bead 3 intermediate the top and bottom of the torch. Connected to the flat top 4 of the upper part or section 1 is a spout 5, which is connected to the section 1 by a nut 6. A wick 7 extends through the spout 5 and may be impregnated with kerosene, which is supplied to the interior of the torch through a filling opening 8 also in the top of the torch. A plug 9 is screwed into the filling opening 8 and forms a closure therefor.

Torches of this character, which serve as signals to vehicles that the road way is under construction, are frequently knocked over, and in order to make this torch self-righting, a counter-weight 10 of lead or other suitable material, is placed in the bottom of the lower section 2. The material forming the counter-weight may be poured into the section 2 in a molten state, or it may be pre-formed by molding in a suitable form, and thereafter placed in the section 2. The counter-weight 10 covers the entire bottom of the section 2, and the sides conform to the sides of the torch, the weight being of substantial thickness to provide an efficient counter-weight for the body of the torch.

In order securely to hold the counter-weight 10 in place, an internal annular bead 11 projects inwardly over the top of the counter-weight 10, and closely embraces the

upper edge thereof. This bead may be of substantial width, and is preferably formed before the sections 1 and 2 are connected together. This bead may be formed by spinning the section 2, and by pressing a suitable tool against the outer surface, the metal may be readily forced inwardly. As shown, a reversely curved groove 12 is formed on the outer surface of the section 2, thereby giving the torch a unique and attractive appearance.

Another method of forming the head 11 is by confining the sides of the section 2 above the counter-weight and pressing the bottom of the section toward its open end. The outer side is confined so that the metal cannot be forced outwardly, and a portion of the inner side is confined so that the metal can only be forced inwardly thereby forming the bead 11 above the counter-weight and holding the same securely in position.

It will be seen that I have provided a serviceable construction torch, which will automatically right itself when knocked over, and which may be constructed from sheet metal at a relatively low cost. This torch, because of its sheet metal construction, is considerably lighter than the cast iron torches which have heretofore been used, and is much more practical for the purpose, especially in view of the self-righting feature.

While I have described my improved torch in more or less detail to comply with the requirements of the statute, it is nevertheless desired that this detailed description be considered merely as illustrative and not as limiting, and it is to be understood that changes and modifications may be made by those skilled in this art without departing from the invention as defined in the following claim.

What I claim as new and desire to secure by Letters Patent is:

The method of securing a counter-weight in the bottom of a sheet metal body section having a closed end and an open end which consists in confining the outer side of the body and a portion of the inner side, and pressing the closed end toward the open end thereby to form a bead over the counter-weight for securing the latter against displacement.

In testimony whereof I have hereunto signed my name to this specification.

LYMAN W. CLOSE.
